Patented June 1, 1920.

Inventor:

Charles A. Xardell,
by Robert Kellum,
Atty's.

UNITED STATES PATENT OFFICE.

CHARLES A. XARDELL, OF UTICA, NEW YORK.

TANK.

1,341,965.

Specification of Letters Patent.

Patented June 1, 1920.

Application filed January 22, 1920. Serial No. 353,291.

To all whom it may concern:

Be it known that I, CHARLES A. XARDELL, a citizen of the United States, residing at Utica, in the county of Oneida and State of

5 New York, have invented or discovered certain new and useful Improvements in Tanks, of which the following is a specification, reference being had therein to the accompanying drawing.

10 This invention relates to tanks, and more particularly to that class of tanks used in automobiles for holding gasoline, and the invention has for its object to provide a tank of this class with means whereby it

15 may be attached in place, as when suspended from a frame. To this end the improved tank comprises a sheet metal body and relatively heavy metal end heads formed either by casting or forging and which

20 heads are provided with integral brackets by which the tank may be mounted in place. To securely hold the end heads in their proper positions in the tank the sheet metal body of the tank is preferably crimped 25 against the inner peripheral edges of the end heads.

In the accompanying drawing, which is a sectional view of the improved tank, 12 denotes the sheet metal body of the tank, and 30 18 the end heads thereof, said heads, which are of cast or forged metal, being provided with integral brackets 14 having holes or openings 15 for bolts or the like by which the tank may be attached in place or suspended from a frame. In order to securely hold the end heads in place the sheet metal body of the tank is preferably provided 35 with indented crimped portions 16 which engage the inner peripheral shoulder parts 40 or edges of the heads 15 and thus, in cooperation with the out-turned flanges 17 on the heads and the locking hooked portions 18 on the tank body, hold the heads in place, notwithstanding the strain said heads may 45 be subjected to in sustaining the weight of the tank and its contents. The improved tank is preferably provided with a baffle plate such as is covered by my U. S. Patent

No. 1,310,517.

50 The supporting brackets 14 extend outward horizontally from the heads 13 and

are preferably located above the central portions of said heads, so that the center of gravity of the tank will be below the supports therefor.

55

From the foregoing it will be understood that the integral brackets 14 with which the forged or cast metal heads 13 are provided, afford convenient means for mounting the tanks in place, and that the crimped portions 16 of the tank body 12, in coöperation with flanges 17 and hooked parts 16, affording interlocking joints, serve to hold the heads 13 firmly in place.

Having thus described my invention, I 65 claim and desire to secure by Letters Patent:

1. A tank consisting of relatively heavy metal end heads provided with integral, horizontally extending brackets located above the central portions of said end 70 heads and by means of which brackets said tank may be mounted or secured in place, and a relatively light sheet metal body portion interlocked with said heads.

2. A tank consisting of relatively heavy 75 metal end heads provided with integral horizontally extending brackets located above the central portions of said end heads and by means of which brackets said tank may be mounted or secured in place, and a 80 relatively light sheet metal body portion interlocked with said heads, the said sheet metal body portion being crimped or indented so as to abut against the inner peripheral shoulder parts of the said end 85 heads and thus serving, in coöperation with the interlocked parts of said heads and body, to securely hold the said heads in place.

3. A tank consisting of relatively heavy 90 end heads having integral, horizontally extending brackets projecting outward from said heads and provided with openings, adapted to receive bolts or the like, and with out-turned flanges, and a sheet metal 95 body portion having hooked portions interlocked with said flanges and having also indented crimped portions engaging shoulders on said heads.

In testimony whereof I affix my signature. 100

CHARLES A. XARDELL.
